UNITED STATES PATENT OFFICE.

BENJAMIN HELLER, OF CHICAGO, ILLINOIS.

METHOD OF SEALING CLOSED CONTAINERS.

Application filed November 4, 1922. Serial No. 593,989.

To all whom it may concern:

Be it known that I, BENJAMIN HELLER, a citizen of the United States, residing at Chicago, in the county of Cook and State of Illinois, have invented certain new and useful Improvements in Methods of Sealing Closed Containers, of which the following is a specification.

The primary object of this invention resides in an improved method of sealing closed containers, wherein it is an impossibility to open the containers, or in some instances, to even tamper with the same without breaking the seal.

A further object of the invention resides in a method of sealing containers that may be employed with all types of containers having widely varied forms of closures, in a simple, cheap and expeditious manner.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:

Figure 1 is a vertical cross sectional view of one form of container, showing the cover for the same sealed by my improved method.

Figure 2 is a top plan view of the container shown in Figure 1.

Figures 3 and 4 are vertical cross sectional views of different types of containers, also showing the covers for the same sealed in accordance with my improved method, and

Figure 5 is a fragmentary top plan view of the container shown in Figure 1, showing the cover thereof sealed in a slightly modified manner.

In describing my method, and referring to the drawings, there is shown in Figures 1 and 2, a barrel including side staves 1, hoops 2, a bottom 3 and a closure 4. In adapting my method to this type of container, the bottom 3 has formed therein a pair of spaced perforations 5, preferably centrally thereof. Preliminary to filling this container, a round or flat wire band of metal or any suitable string or tape 6 is adapted to have its opposite ends engaged through the spaced per-

forations in the bottom of the barrel. The opposite ends of the string, or tape, or round or flat, wire band of metal 6 is then brought upwardly within the barrel and has its extreme outer ends positioned over the sides thereof. When this has been done, the barrel may be filled.

The cover 4 is also provided with a pair of similarly spaced perforations 7 and before applying this cover to the barrel, the ends of the string or tape 6 are threaded through these perforations 7 to be held outwardly of the cover while applying the same. After the cover has been applied, the string or wire is drawn taut within the barrel, and the portions extending outwardly of the cover are layed over as at 8 upon the cover, and are then sealed by a sealing medium 9.

The application of my method to the type of container shown in Figure 3, in which figure, the container comprises a body 10 having the well-known type of slip cover 11, the steps are substantially the same as those described for the container shown in Figures 1 and 2.

In Figure 4, I have shown my method of sealing containers as being applied to a container having a screw closure. In this figure, 12 indicates the container, and 13 the screw closure. In this type of container, the steps are substantially the same as those employed in sealing the containers shown in Figures 1, 2 and 3. This is true with the exception of the fact that in securing the cap 13 upon the container, the cord or the like 6 is allowed to feed into the container for permitting the same to be wound upon itself as at 14. After the top is in proper position upon the container, the ends of the cord are pulled for tightening the cord within the container, at which time, the ends thereof are sealed as at 9 as above described. In this instance, it will be seen that the screw cap is allowed to be screwed in a reverse direction at a slight distance upon the container in view of the coiled portion 14 of the cord, but the nature of this coiled portion is such as to prevent total disengagement of the cap from the container.

In the modification shown in Figure 5, the ends of the string, tape or wire 6 is also passed through spaced perforations in a disk seal 15 of tin or the like, after the cover 4 has been positioned in place. The extreme ends of the cord or tape 6 are then coiled as

shown to be secured together by a usual lead seal 16.

While I have herein shown and described an improved method for sealing closed containers, it is nevertheless to be understood that slight deviations may be departed from without effecting the spirit and scope of the invention as claimed.

What I claim as new is:—

10. In a method of sealing closed containers wherein a pair of spaced perforations are provided within the bottom of the container, inserting the opposite ends of a band of wire

or tape through these perforations, extending the ends of the wire or tape upwardly 15 within the container and allowing the same to engage over the sides thereof, then filling the container and engaging the opposite ends of the wire or tape through a pair of spaced perforations in the top of the container, applying the top to the container, tightening the wire or cord within the container, and then sealing the projecting ends of the cord upon the top thereof.

In testimony whereof I affix my signature.
BENJAMIN HELLER.
